UNITED STATES PATENT OFFICE.

GEORGE WILLIAM RUSSELL, JR., OF DENVER, COLORADO.

SWITCH.

SPECIFICATION forming part of Letters Patent No. 499,646, dated June 13, 1893.

Application filed April 7, 1893. Serial No. 469,488. (No model.)

To all whom it may concern:

Be it known that I, GEORGE WILLIAM RUSSELL, Jr., a citizen of the United States of America, residing at Denver, in the county of

5 Arapahoe and State of Colorado, have invented certain new and useful Improvements in Circuit-Switches; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 My invention relates to improvements in circuit switches and the object of the improvement is to provide a device of this class which shall be simple in construction, economical in cost, reliable, durable and efficient in use.

20 To this end my improved electrical switch consists of the features, arrangements and combinations hereinafter described and claimed, all of which will be fully understood by reference to the accompanying drawings in which 25 is illustrated an embodiment thereof.

In the drawings, Figure 1 is a front elevation of the device in detail. Fig. 2 is a side elevation of the same. Fig. 3 is a section taken on the line $x-x$, Fig. 2. Fig. 4 is an 30 underneath view of the mechanism. Fig. 5 is a diagrammatic view illustrating two switches in circuit.

For the purposes of this specification, I shall assume that the device occupies an upright 35 or vertical position, the top of which is toward the top of the sheet of drawings. This assumption, however, is only for convenience of description, as the operation of the mechanism is equally effective in whatever position it may be placed.

Similar reference characters indicating corresponding parts or elements of the mechanism in the several views, let the numeral 5 designate a suitable supporting plate, to the 40 top of which is attached a double hanger composed of two parts 6, to which is pivoted the lever 7 composed of some material forming good conductor for the electrical current. This rocking lever is operated by means of 45 push buttons 8 which pass through suitable apertures formed in the top of the supporting plate. These buttons are connected with the

lever by means of links 9 which are pivoted to the lever at points 12 on either side of its fulcrum 10; the opposite extremities of the 55 links are pivoted to the buttons as shown at 13. The lever 7 is preferably double, its two parts being connected at either extremity as shown at 7^a. At a point on the lever located on a vertical line with its fulcrum when the 60 lever is in a horizontal position, is attached one extremity of a coil-spring 14 which is always under tension. The spring is preferably double as shown in Fig. 2, the connection between its two parts being passed under a pin 65 15 located between, and connecting the two parts of the lever, the upper extremities of the spring being attached to the top of the supporting plate.

To the inner surface of the supporting plate 70 or casing 5 are attached three contacts, 16, 16 and 17, connected with the binding posts 18, 18 and 19, whose extremities project through the casing 5. The contact 17 is centrally located and is always in engagement with the 75 rocking lever, while the two contacts 16 are alternately in engagement therewith.

This switch is specially designed for use in an incandescent lamp circuit and is so illustrated in Fig. 5. When it is desired to control the same lamp or lamps from two distinct and separate points, as from two compartments of a building, the three contacts 16, 16 and 17 are employed as shown in Fig. 5. When, however, it is desired to control the lamp or 85 lamps from but one point, only one of the contacts 16 is essential, as will be readily understood.

The circuit illustrated in Fig. 5 will now be described. Let the numerals 20 and 21 designate the main circuit conductors. From conductor 21 leads a branch wire 22 to the lamp 23, which is connected with the contact 17 of one switch A by means of a wire 24, while the contact 17 of the other switch B is 90 connected with the main conductor 21 by a wire 25. The two contacts 16 farther to the left in the two switches are connected by a wire 26, while the other two contacts 16 are connected by a wire 27. Assuming that the 95 rocking levers are in the position shown in full lines in Fig. 5, the electric current may be said to pass from main conductor 20 through wire 22 to the lamp, and thence through wire 100

24 to contact 17 of switch A, and thence through the lever 7 to contact 16, and thence via wire 26 to one contact 16 of the switch B, thence through the rocking lever to contact 17 and to the other main conductor 21 through medium of wire 25. In this case the lamp circuit is closed. Again if the two levers of switches A and B are both in the dotted line position, the path of the current may be said 5 to be from main wire 20 through branch wire 22 to the lamp, and thence through wire 24 to contact 17 of switch A, through lever 7 to contact 16, and thence through wire 27 to the corresponding contact 16 of switch B, and thence 10 through the lever to contact 17 and to the other main conductor 21 via wire 26. It will thus be seen that when the circuit is closed, the two levers must be in corresponding positions. However, when it is desired to extinguish the 15 lamp it is only necessary to reverse the position of either lever. For instance, if the lever of switch A is in the dotted line position, and the lever of switch B is in the full line position, I find the circuit is broken between lever 7 of switch B and the contact 16 farther to the right. Again, if the lever of switch A is in the full line position and that of switch B in the dotted line position, there is a break 20 in the circuit between the lever of switch A and the contact 16 farther to the right of the same switch.

It will be readily seen that if it is desired to control the lamp from but one point, but one switch will be necessary. For instance, 25 if I dispense with switch B, the light may be controlled from switch A alone, and only one wire 26 or 27 will be employed and this wire will lead directly from the corresponding contact 16 to the main circuit wire 21.

Having thus described my invention, what 30 I claim is—

1. In a circuit switch, the combination of a rocking lever suitably supported, a coil-spring attached to the support at one extremity above the fulcrum of the lever, and at the other extremity to the lever below the fulcrum and three contacts, one of which is always in engagement with the lever, while the other two are alternately in contact, therewith substantially as described. 45

2. In a circuit switch, the combination of a rocking lever, a coil-spring attached at one extremity to a stationary support above the lever fulcrum, and at the other extremity to the lever at a point below the fulcrum and two contacts, one in continuous engagement with the lever, and the other in disengagement or engagement therewith, according as the circuit is closed or broken, substantially 50 as described. 55

3. In a circuit switch, the combination with the circuit of a rocking lever, a double coil-spring having its extremities attached to a stationary support above the lever fulcrum and its center attached to the lever below the fulcrum, and suitable contacts, substantially 60 as described. 65

4. In a circuit switch, the combination with the circuit, of a rocking lever, a coil-spring attached at one extremity to a stationary support, and at its opposite extremity to the lever at a point below the fulcrum, the two points of attachment for the spring lying in the same vertical line with the fulcrum of the lever, and suitable contacts, substantially 70 as described. 75

In testimony whereof I affix my signature in the presence of two witnesses.

GEORGE WILLIAM RUSSELL, JR.
